United States Patent Office.

CHARLES BREASTED, OF CHICAGO, ILLINOIS.

Letters Patent No. 77,578, dated May 5, 1868.

BARREL-SIFTER.

The Schedule referred to in these Letters Patent and making part of the same.

TO ALL WHOM IT MAY CONCERN:

Be it known that I, CHARLES BREASTED, of Chicago, in the county of Cook, and State of Illinois, have invented certain new and useful Improvements in Sifters for Coal-Ashes; and I do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use my invention, I will proceed to describe it.

My invention relates to ash-sifters or screens, and consists in a novel construction and arrangement of devices, by which the operator can conveniently and thoroughly separate the ashes from the unburnt or partially burnt coal without being annoyed by any dust.

In the drawings—

Figure 1 is a view of a vertical section taken on the line *y y* of fig. 2, and

Figure 2 is a view of a vertical section, taken on the line *x x* of fig. 1.

In constructing my ash-sifter, I make a strong box, A, as shown in figs. 1 and 2, and provide it with a cover, B, hinged at *e*, as shown in fig. 2. In the upper part of the box A, I place a concave inclined slide, C, and extend it about two-thirds of the way from the front to the rear or opposite side of the box A, as shown in fig. 1, and to the inner sides of the box A, about the inclined slide C, I attach inclined projections, so that all the coal and ashes thrown into the top of the box A will slide down and fall through the opening at the lower end of the inclined slide C. The inclined projections *g*, I construct so that on two sides of the box A the inclined slide C may be supported by and attached to them, as shown clearly in fig. 2.

Immediately underneath the slide C and projections *g*, I place a frame, D, within the box A, so as to extend from its inner front to its inner rear side, as shown in fig. 1, but about one-fourth narrower than the box in the opposite direction, as shown in fig. 2, and mount it on rollers *a*, arranged to run on supporting-pieces *h*, attached to the inner side of the box A, and near its bottom, as shown in fig. 1.

Within the frame D, I place a wire screen, E, constructed as shown in fig. 2, and so as to extend diagonally from the upper rear to the lower front side of the frame D, as shown in fig. 1. At the lower side of the frame D, where the screen E terminates, I make a rectangular opening, and attach to the frame D a delivery-spout, *b*, which projects through a corresponding opening in the front of the box A, sufficiently large to allow of a lateral movement of the delivery-spout corresponding with the lateral movement of the frame D. To the outside of the box A, and so as to surround the spout *b*, I attach a cover, *c*, with an opening, *d*, on its under side. The spout *b*, I make so that its bottom and sides may be continuations of the bottom and sides of the opening in the frame D.

To the under side of the box A, which has an open bottom, I attach a metal or other suitable circular projecting rim, *F*, for setting the box on a barrel, *G*, or other receptacle for ashes, and to the frame D a handle, *H*, which passes loosely through the side of the box A, as shown in fig. 2.

In operating my sifter, I throw the coal and ashes, or other substance to be sifted, into the upper part of the box A, and as it slides down and off the concave inclined slide C on to the inclined screen E, I give the screen a rapid reciprocating motion by means of the handle *H*, which causes the ashes to separate from the coal and fall through into the barrel *G*, while the coal or other substance too coarse to pass through the screen, slides down and drops out of the hole *d*, as shown in fig. 1.

During this operation no dust can arise, as the whole is confined within the close box A, and the rim *F* prevents any from rising from the barrel *G*. It can be used within the house, if desired, without annoyance from dust. It does its work thoroughly, and thus secures a great saving of useful material that is otherwise wasted. It is simple in its construction and operation; cleanly in its work; not easily gotten out of repair or injured; can be made at little cost, and used by the most unskillful.

Having thus described my invention, what I claim is—

An ash-sifter or screener, consisting of the box A, provided with the concave inclined slide C and laterally moving frame D, having the inclined screen E and mouth *b* attached, and protected by the cover *c*, all constructed and arranged to operate substantially as herein described.

CHARLES BREASTED.
